(57) **CLAIM**

The ornamental design for a wireless indoor environment sensor, as shown and described.

DESCRIPTION

FIG. 1 is a perspective view of an exemplary embodiment of a wireless indoor environment sensor showing our new design.

FIG. 2 is a left elevation view of the wireless indoor environment sensor of FIG. 1.

FIG. 3 is a right elevation view of the wireless indoor environment sensor of FIG. 1.

FIG. 4 is a front elevation view of the wireless indoor environment sensor of FIG. 1.

FIG. 5 is a rear elevation view of the wireless indoor environment sensor of FIG. 1.

FIG. 6 is a top plan view of the wireless indoor environment sensor of FIG. 1; and,

FIG. 7 is a bottom plan view of the wireless indoor environment sensor of FIG. 1.

The broken lines shown are included for the purpose of illustrating portions of the wireless indoor environment sensor that form no part of the claimed design.
